UNITED STATES PATENT OFFICE.

ALEXANDER MIKLEA, OF DETROIT, MICHIGAN.

PERMUTATION-LOCK-CONTROLLED MAIL-BOX.

1,247,133.

Specification of Letters Patent. Patented Nov. 20, 1917.

Application filed September 1, 1917. Serial No. 189,361.

To all whom it may concern:

Be it known that I, ALEXANDER MIKLEA, a subject of the King of Hungary, residing at Detroit, in the county of Wayne and State of Michigan, have invented certain new and useful Improvements in Permutation-Lock-Controlled Mail-Boxes, of which the following is a specification.

This invention relates to certain new and useful improvements in permutation lock controlled mail box.

The primary object of the present invention is the provision of a mail box adapted to receive pieces of mail such as letters, readily deposited therein arranged with a letter-delivering apparatus under the control of a permutation lock mechanism, whereby a person unfamiliar with the combination of the lock will be unable to gain access to the mail within the box.

A further object of the invention is the provision of a safety appliance especially adapted for mail-receiving boxes arranged in hallways of houses and similar readily accessible points whereby the mail can be readily delivered from the box by the manipulation of permutation lock members by persons familiar with the combination, while the arrangement is such that the mail cannot be extracted or delivered exteriorly of the box without first releasing the lock.

With these general objects in view and others that will appear as the nature of the invention is better understood, the same consists in the novel combination and arrangement of parts hereinafter more fully described, illustrated in the accompanying drawings, and then claimed.

In the drawings forming a part of this application, and in which like designating characters refer to corresponding parts throughout the several views,

Figure 1 is a front elevation of the device, Fig. 2 is a vertical longitudinal sectional view of the same.

Fig. 3 is a vertical sectional view thereof taken upon a plane perpendicular to the plane of section of Fig. 2,

Fig. 4 is a horizontal transverse sectional view of the device,

Fig. 5 is a view of the lock mechanism in its secured arrangement and

Fig. 6 is a similar view with the lock released.

Referring more in detail to the drawings, the mail box 10 is herein illustrated having

a front plate 11 provided with a mail-receiving slot 12 arranged with a swinging guard 13 positioned therein. The plate 11 is of the form commonly employed with mail boxes for houses and especially apartment houses, being arranged with a mouth-piece 14 for a speaking tube, not shown, and with a push-button 15 serving as a door-bell.

A curved partition 16 is provided in the box 10 terminating forwardly at its upper end slightly beneath the slot 12 as at 17 while the rear wall 18 of the box is similarly curved, it being understood that letters such as 19 may be readily inserted through the slot 12 which will fall between the partition 16 and wall 18 toward the bottom 20 of the box. Sight tubes are provided through the plate 11 and partition 16 for determining the presence of mail matter within the box, the said tubes preferably having transparent windows 22 at their outer ends.

An elevator 23 is arranged for the mail in the form of a platform vertically slidably positioned within the mail-receiving chamber 24 of the box, an arm 25 being carried by the platform and extending through a longitudinal slot 26 in the partition 16, a sleeve 27 being arranged upon the arm slidably positioned upon a curved guide-rod 28 arranged forwardly of the partition 16 within the mechanism-chamber 29 of the box and adjacent the slot 26. The rear end of the elevator 23 is in the form of a flange 30 while rollers 31 are carried by the rear portion of the elevator for moving upon the rear wall 18 of the box and rollers 32 are carried by the front edge thereof for moving upon the partition 16.

The elevator 23 is normally positioned adjacent the bottom 20 of the box 10 and it will be evident that a letter 19 will fall upon the elevator when placed through the slot 12 as best illustrated in Fig. 2 of the drawings while an upward movement of the elevator 23 will force the letter 19 outwardly through the slot 12 in the dispensing operation as illustrated by dotted lines in the said figure.

A lock casing 33 is arranged upon the inner side of the plate 11 within the chamber 29 of the box, a permutation lock 34 being provided for the said casing having the usual dial 35 arranged outwardly of the plate 11 and provided with an operating knob 36. An operating button 37 for the elevator 23 is arranged outwardly adjacent

the knob 36 being provided with a shaft 38 freely journaled through the knob 36 and the casing 33 and provided with a gear 39 upon its inner end within the box chamber 29. Opposite winding spools 40 and 41 are arranged upon stub-shafts 42 and 43 respectively journaled through the rear plate 44 of the casing 33. Pinions 45 and 46 are provided upon the shafts 42 and 43 respectively 10 in constant mesh with the gear 39 and whereby the turning of the said gear by means of the button 37 will revolve the pinion as well as the spools 40 and 41 in opposite directions.

15 A cord 47 is attached to the sleeve 27 as at 48 and passes over a pulley 49 adjacent the top of the partition 16 and thence to the spool 41 to which it is secured as at 50. A similar cord 51 is attached to the sleeve 27 20 as at 52 and after passing over a pulley 53 upon the bottom 20 of the box 10 passes to the spool 40 and is secured thereto as at 54. An elongated pulley 55 is carried by the casting lid 44 above the pinions 45 and 46 adapted for preventing the cord 47 from interfering with the operation of the said pinions. It will be understood that when the elevator 23 is in its lowered position, the button 37 25 may be turned for revolving the gear 39 in the direction indicated by the arrow in Fig. 3 of the drawings and the spool 41 will be thereby turned for winding up the cord 47 and elevating the member 23 with the letter 19 while the cord 51 is being unwound from 30 the opposite spool 40. A reversal of the direction of movement of the button 37 returns the elevator 23 to its lowered position while the weight of the elevator is also serviceable in lowering the same.

35 The bolt 56 is arranged for the lock 34 adapted to be automatically projected by a spring 57 when released from the foot 58 of a latch 59 arranged with an elevating spring 60. A star wheel 61 is arranged upon the inner end of the shaft 43 of the pinion 46 and spool 41 and is positioned within the path of movement of a tooth 62 carried by the adjacent end of the bolt 56. An operating lever 63 is pivoted upon the bolt 56 40 having an angular end 64 positioned upon the peripheries of the disks 65 and 66 of the lock 34 when the latch 59 is depressed by the adjacent end 67 of the lever 63 as illustrated in Fig. 5 of the drawings. At such 45 times, the star wheel 61 being engaged by the tooth 62 prevents any rotation of the gear 39 by means of the button 37. Upon bringing the notches 68 and 69 of the permutation members 65 and 66 respectively 50 into alignment with the lever end 64, which end under the influence of the depressing spring 70 forces said end 64 into the said notches so that the turning of the member 66 in the direction indicated by the arrow 55 in Fig. 5 of the drawings will engage the shoulder or end 71 of the notch 69 with the lever end 64 and force the bolt 56 to its retracted position as illustrated in Fig. 3. The tooth 62 is disengaged from the wheel 61 and the disengaging of the foot 58 of the latch 59 from beneath the bolt 56 permits the spring 60 to elevate the latch, bringing the foot 58 adjacent the end 72 of the bolt and preventing the spring 57 from projecting the bolt until the latch is released. Upon turning the disk 66 in the direction reverse to that indicated by the arrow in Fig. 6 of the drawings, the lever end 64 will be elevated out of the notches 68 and 69 for riding upon the peripheries 80 of the disks 65 and 66. The lever 63 being pivotally shifted by this operation, the end 67 thereof will depress the latch 59, releasing the foot 58 from the face 72 of the bolt 56 and permitting the spring 57 to project 85 the bolt to its locked position with the tooth 62 engaging the star wheel 61 as shown in Fig. 5. The locking of the star wheel 61 prevents the turning of the button 37 so that the operation of the elevator is rendered impossible.

90 A serviceable dispenser for mail from a deposit receptacle is arranged which is under the control of a permutation lock so that a person familiar with the combination of the lock may readily release the bolt 56 so that the button 37 may be turned while a person unfamiliar therewith will be unable to release the lock and consequently cannot obtain access to the mail matter within the chamber 24.

95 What I claim as new is:—

1. A mail box having a receiving slot therein, an elevator within the box, operating means for the elevator and lock controlling mechanism for the operating means. 105
2. A mail box having an entrance slot, a mail elevator vertically shiftably arranged within the box, an operating button for the elevator arranged outwardly of the box, operative connections between the said button and elevator and a permutation lock adapted for restraining engagement with the said connections operable adjacent the said button. 110
3. A mail box having an entrance slot in its front plate adjacent the upper end thereof, a curved partition within the box terminating at its upper end beneath the said slot and arranged with a longitudinal slot, an elevator within the box adapted for the reception of mail matter inserted through the said entrance slot, an arm carried by the elevator extending through the slot of said partition, a curved rod arranged forwardly of the partition, a sleeve upon said arm, slidably positioned upon the said rod, elevating and lowering cords for the elevator attached to the said sleeve, oppositely operable pulling means for the said 115

- 125
- 130

- cords, operating means for the said pulling means and a permutation lock having a bolt operatively associated with the said operating means.
- 5 4. A mail box having an entrance slot in its front plate adjacent the upper end thereof, a curved partition within the box terminating at its upper end beneath the said slot and arranged with a longitudinal slot, an elevator within the box adapted for the reception of mail matter inserted through the said entrance slot, an arm carried by the elevator extending through the slot of said partition, a curved rod arranged 10 forwardly of the partition, a sleeve upon said arm, slidably positioned upon the said rod, a lock casing, a shaft journaled through the casing, an operating button upon the outer end of the shaft, a gear upon the inner end of said shaft, pinions meshing with the said gear, spools carried by the said pinions, oppositely extending cords attached at their adjacent ends to the said sleeve and at their opposite ends to the said spools and 15 a permutation lock having a bolt adapted for restraining the movement of one of said gears.
5. A device of the class described comprising a box having an entrance slot, a curved partition within the box, terminating adjacent 20 said slot and forming a mail-receiving chamber, sight tubes arranged through the front plate of the box and the said partition, a mail elevator vertically shiftably arranged within said chamber, a lock casing within the box, operating means for the elevator attached to the latter and adapted for actuation forwardly of the box, permutation locking means for the said operating means arranged within said casing and operable 25 exteriorly thereof.
6. A device of the class described comprising a box, a mail elevator therein, a casing within the box, an operating shaft for said elevator journaled through the casing, operative connections between the said shaft and elevator, a star wheel associated with said connections, and a permutation lock for the said casing having a shiftable bolt operatively associated with the said wheel and operable exteriorly of the box.

In testimony whereof I affix my signature.

ALEXANDER MIKLEA.
